UNITED STATES PATENT OFFICE.

JOHN A. DEIGNAN AND HENRY J. POLLACEK, OF NEW YORK, N. Y.

WATER-CLOSET.

1,119,812.

Specification of Letters Patent.

Patented Dec. 8, 1914.

Application filed September 8, 1913. Serial No. 788,512.

To all whom it may concern:

Be it known that we, JOHN A. DEIGNAN and HENRY J. POLLACEK, citizens of the United States, and residents of New York, 5 in the county of New York and State of New York, have invented certain new and useful Improvements in Water-Closets, of which the following is a specification.

This invention relates to water closets 10 and consists of certain novel arrangements of high pressure water supplies which are delivered into the outlet pipe of the bowl to force the contents of the bowl outward by suction and as an overflow to fall into 15 the bowl from its upper rim, the latter supply being discharged from a muffler into a pocket at one side of the bowl and carried to the overflow gutter in the rim through side passages, the object of the invention 20 being to supply the clearing water without the usual noises which are so objectionable in the form of bowl now in use, as will be more fully described in the following specification, set forth in the claims and illustrated in the accompanying drawings, 25 wherein:

Figure 1. is a longitudinal sectional view of the improved bowl and the supply valve. Fig. 2. is a cross sectional view of the bowl. 30 Fig. 3. is a detail view of the muffler.

In the flushing of water closet bowls it is usual to supply the necessary pressure to the water by means of tanks located at various elevations to afford sufficient fall to 35 the water to carry off the heavy foul water and this sudden rush of water results in noises of greater or less degree, and it is to overcome these objectionable features that the present invention is designed.

The bowl 5 as shown in the drawings is 40 similar in shape to the ordinary bowl and has its outlet 6 at the front end and which is a siphon with one end terminating at the bottom of the bowl while the other end connects with the pipe 7 leading to the sewer. The upper rim 8 of the bowl is hollow and on the inside of the bowl is provided with a plot 9 of less width than the inside diameter of the hollow rim so as to leave a gutter 10 around the entire interior of the bowl. At one side of the bowl, and preferably the rear side, is a chamber 11 communicating by means of the two side passages 12 with the hollow rim and the gutter 10, and fitted 55 within this chamber is the muffler 13 consisting of a metal cup with staggered slots 14,

around its sides and through which the water issues to fill and overflow the gutter 10 when the balance of the flushing water is supplied to a passage 15 terminating in 60 a nozzle 16 to issue into the inner end of the siphon and force the contents of the bowl out of the pipe 7.

The water supply may be from an ordinary pressure or high pressure main and 65 when divided for the above described discharges will be found abundant to properly flush and cleanse the tank and this supply is furnished through the inlet pipe 17 into the valve chamber 18, and is released by the valve 19 when pressure is applied to the knob 20. The spring 21 is sufficiently 70 strong to resist the pressure of the water, but when the water passes the valve it is divided, one part passing to the muffler 13 75 through the pipe 22 while the other portion passes through the trap 23 and into the pipe 24 and the passage 15. The supply of water to the nozzle 16 and the gutter 10 is regulated by the valves 25 and 26, so that the 80 pressure may be reduced at each of the outlets. It will therefore be seen that any sound following the issue of water from the nozzle is drowned in the outgoing water and any hissing or splashing of the discharge is so far in the siphon that it will not 85 be heard on the outside. The water passing from the muffler will be noiseless and the overflow from the gutter simply drips into 90 the bowl to be carried off by the nozzle 16.

The construction of the bowl is very simple and no resistance is offered to the outward movement of the water while the overflow is simple and noiseless.

The metallic connections may be by means 95 of screws and are accessible while the regulation of the water supplies may be instantly performed.

It is obvious that the details may be modified and the parts otherwise arranged without departing from the essential features above described, or the scope of the appended claims.

What we claim as new and desire to secure by Letters Patent is:

1. In water closets, the combination with 105 a bowl having a gutter in its rim, a muffler chamber and passages in its walls comprising trapped side communications between the muffler chamber and the gutter in the 110 rim of the bowl and a trapped inlet nozzle at the bottom of the bowl, of a muffler in

the muffler chamber, water supply pipes for the muffler and the inlet nozzle, and a valve controlling the supply pipes.

2. In water closets, the combination with
5 a bowl having a muffler chamber, a slotted hollow rim communicating by means of trapped passages with the muffler chamber and a passage terminating in an outlet nozzle in the bottom of the bowl, of a trap for
10 the latter, supply pipes for the trap and the muffler chamber, and a valve controlling the same.
3. In water closets, the combination with
a bowl having a hollow slotted rim and a
15 muffler chamber connected with each other

by means of trapped passages, of a discharge pipe with a nozzle terminating in the outlet of the bowl, a trap in the discharge pipe, a muffler in the chamber, and a pipe controlled by a valve supplying the 20 muffler and the discharge pipe with water.

Signed at New York in the county of New York and State of New York this 20th day of August A. D. 1913.

JOHN A. DEIGNAN.
HENRY J. POLLACEK.
